United States Patent Office.

NICHOLAS S. VEDDER, OF TROY, AND TOBIAS S. HEISTER, OF LANSINGBURG, NEW YORK, ASSIGNORS TO J. L. MOTT, OF NEW YORK CITY.

Design No. 4,464, dated November 8, 1870.

DESIGN FOR A RANGE OR STOVE.

The Schedule referred to in these Letters Patent and making part of the same.

To all whom it may concern:

Be it known that we, NICHOLAS S. VEDDER, of Troy, and TOBIAS S. HEISTER, of Lansingburg, in the county of Rensselaer and State of New York, have jointly invented and produced a Design for Plates of a Range or Stove, of which the following is a specification, reference being had to the accompanying photographic representation of a cooking-range having our said design.

One part of our said design consists of the compound ornament A and ribbed tablet B, shaped and arranged together upon and cast in one and the same piece with a door or plate, C, of a stove or range, substantially as shown in the aforesaid photograph.

Another part of our design consists of the combination of the compound ornament A, ribbed tablet B, and border-molding D, all shaped and arranged upon and cast with a plate or door of a range or stove, so as to present the appearance represented in the photograph.

Another part of our invention consists of the ornamental design for the door or plate E, as distinguished by the border-molding f, plane surface g, tablet h, and center ornament i, all shaped and disposed so as to appear as shown in the said photograph.

Another part of our invention is the design for the fire-door J, as distinguished by the ornamented, swell-

ing ash-pit cover k, register l, and corner ornaments m, all shaped and arranged on the door so as to appear as represented in the photograph aforesaid.

Another part of our invention is the particular design for the leg M, as shown in the accompanying photograph.

What we claim as our invention, and desire to secure by Letters Patent, is—

1. The combination of the compound ornament A and raised tablet B, when shaped and arranged together upon and cast with a door or plate, C, of a stove or range, as herein shown and described.

2. The combination of the ornament A, tablet B, and border-molding D, when shaped and arranged together and cast with a door or plate of a range or stove, as described and shown.

3. The design for the plate E, as shown and described.

4. The design for the fire-door J, as described and shown.

5. The design for the leg M, as shown.

NICHOLAS S. VEDDER.
TOBIAS S. HEISTER.
